UNITED STATES PATENT OFFICE

164,615

ILLUMINATING CLIP BOARD

Charles Ellis Warnell, Portland, Oreg.

Application October 6, 1950, Serial No. 12,478

Term of patent 14 years

(Cl. D74—1)

To all whom it may concern:

Be it known that I, Charles E. Warnell, a citizen of the United States of America, residing at Portland, in the county of Multnomah and State of Oregon, have invented a new, original, and ornamental Design for an Illuminating Clip Board, of which the following is a specification, reference being had to the accompanying drawing, forming a part thereof.

In the drawings:

Figure 1 is a view in perspective of an illuminating clip board, showing my new design; and

The essential features of my design for an illuminating clip board are shown in full lines in the drawing.

I claim:

The ornamental design for an illuminating clip board, as shown and described.

CHARLES E. WARNELL.
